United States Patent Office.

G. C. WRIGHT, OF LE ROY, OHIO.

Letters Patent No. 70,062, dated October 22, 1867.

IMPROVED APPLE-CORER AND SLICER.

The Schedule referred to in these Letters Patent and making part of the same.

TO ALL WHOM IT MAY CONCERN:

Be it known that I, G. C. WRIGHT, of Le Roy, in the county of Medina, and State of Ohio, have invented a new and improved Machine for Slicing and Coring Apples; and I do hereby declare that the following is a full, clear, and exact description thereof, which will enable others skilled in the art to make and use the same, reference being had to the accompanying drawings, forming part of this specification, in which—

Figure 1 is a vertical longitudinal section of my improved apple-slicing and coring machine.

Figure 2 is a vertical transverse section of the same.

Figure 3 is a detached top view of the cutter.

Similar letters of reference indicate like parts.

This invention relates to an improvement in the construction of a machine for slicing and coring apples, and consists in a slicer or cutter, having a central tubular core-cutter, with a series of radial knives set around it, to slice an apple in segments, by means of a follower brought down upon it with a lever, as hereinafter more particularly described.

The platform A of the machine is fastened to a table or bench in any suitable manner, and in the platform is set a cutter, formed of a central circular-edged coring-knife, a, surrounded with straight-edged slicing-knives e, having their cutting edges on the upper side of the platform, and opening out below it. Under the platform A is attached a sloping trough, B, through which is extended the tubular cutter a. Directly over the cutter a is a vertical follower, C, suspended in a cross-frame, d d, supported by standards D D, in which it is held up by a spiral spring, e, coiled around it. The follower rests upon a lever, E, which operates it by drawing down on a cord, g, or in any suitable manner.

An apple is placed on the cutter, with its core in a vertical position; the follower C is brought down upon it, and the circular cutter a cuts out the core, which passes down below the trough B, while the radial knives e slice the body of the apple into sections, which fall upon the trough and into a basket or other receptacle. The lever rises again by the expansion of the spiral spring e.

Having thus described my invention, I claim as new, and desire to secure by Letters Patent—

In combination with the slicing device, the follower C, vertical spring e surrounding such follower, and the lever E, hung to the post upon the bottom A, all arranged as described, for the purpose specified.
